UNITED STATES PATENT OFFICE.

EMERSON K. WILSON, OF CHERRYFIELD, MAINE.

BAG-HOLDER.

SPECIFICATION forming part of Letters Patent No. 411,701, dated September 24, 1889.

Application filed June 29, 1889. Serial No. 316,003. (No model.)

To all whom it may concern:

Be it known that I, EMERSON K. WILSON, a citizen of the United States, residing at Cherryfield, in the county of Washington and State 5 of Maine, have invented certain new and useful Improvements in Bag-Holders; and I do hereby declare that the following is a full, clear, and exact description of the same, reference being had to the annexed drawings, 10 making a part of this specification, and to the letters and figures of reference marked thereon.

This invention relates to certain new and useful improvements in bag-holders; and it 15 has for its object to provide a device of this character that will be simple and cheap in construction and very efficient in operation.

The invention consists in the peculiar combinations and the construction, arrangement, 20 and adaptation of parts, all as more fully hereinafter described, shown in the drawings, and then particularly pointed out in the appended claims.

The invention is clearly illustrated in the 25 accompanying drawings, which, with the letters of reference marked thereon, form a part of this specification, and in which—

Figure 1 is a perspective view of a bag-holder embodying my improvements, as de- 30 scribed for bagging measured material. Fig. 2 is a like view showing the device applied to a scale for bagging material that has not been measured, but which as it is bagged is designed to be weighed upon the scales.

Referring now to the details of the drawings by letter, A designates a standard 35 formed of two parts a and a', connected together so as to be vertically or longitudinally adjustable, a set-screw b being provided to hold the parts in their adjusted position.

When designed to be used for bagging measured material, I secure this standard to a suitable base, as c, (shown in Fig. 1,) the same being braced by means of a suitable brace, as 40 d. When applied to a scale, the base is omitted and the standard secured to the platform of the scale, as shown in Fig. 2, in any convenient manner. Pivotal secured to the upper part of the standard, as at e, is the 45 holder B, which consists of a preferably metallic support, the forward portion of which is formed with the jaws or arms f, provided

with suitable teeth or holding means g for the bag.

In Fig. 1 this holder is shown as having attached thereto the box or scoop C, to which the teeth are attached, the front side of the scoop or box being cut away, as shown at g', to allow the material to be readily poured therein, forming a rest for the measure, as 55 will be readily understood.

In Fig. 2, where the material is to be weighed, the scoop is dispensed with, the bag being 60 designed to be secured to the teeth on the jaws.

After the bag has been filled it is desirable to remove the strain thereon in order to allow of the removing of the same from the teeth or hooks. In order to do this the holder is pivoted, as above described, on a horizontal 70 pivot e. It is held in its normal position—that shown in the drawings in full lines—by means of a spring-catch D, which consists of a spring-metal plate attached at one end to the standard and at its free end formed with a shoulder 75 g' and a tapered or rounded face h. This engages the rearward extension of the holder, and when the bag has been filled and it is desired to remove the same the spring-catch 80 is moved so as to disengage the said rearward extension, when the weight of the scoop or jaws and the bag will cause the same to drop, as shown by dotted lines. After the bag has been removed the jaws are turned back into 85 their normal position, when the rearward extension thereof rides down the inclined face of the catch, and are automatically locked in position ready to repeat the operation of filling the bag.

By means of a device constructed as above 90 described the process of bag-filling may be carried out very rapidly and with very little trouble or exertion.

What I claim as new is—

1. In a bag-holder, a standard consisting of 95 a stationary part recessed upon its rear side and a vertically-adjustable part fitting within the recess and held in its adjusted position by a thumb-screw, in combination with a spring-catch carried by the adjustable part 100 and a bag-holding device pivotally connected to the upper end of the adjustable part of the standard, and having a rearward U-shaped extension adapted to automatically engage

with said spring-catch, substantially as shown and described.

2. The bag-holder described, consisting of the adjustable standard, the jaws pivotally connected with the upper part of said standard by means of a horizontal pivot and provided with a rearward extension, and a spring-plate attached at its lower end to the rear side of the upper part of said standard, and formed at its upper end with a square shoulder

and forwardly-inclined upper face, substantially as shown and described, and for the purpose specified.

In testimony that I claim the above I have hereunto subscribed my name in the presence 15 of two witnesses.

EMERSON K. WILSON.
